UNITED STATES PATENT OFFICE.

NELS A. JOHNSON, OF JAMESTOWN, NEW YORK.

WRENCH.

Application filed August 11, 1921. Serial No. 491,341.

The invention relates to adjustable jaw wrenches for bolt nuts; and the object of the improvement is to provide a simple adjustable jaw wrench of great strength and durability which has a simple and positive adjustment of the movable jaw, the jaws being held in comparatively perfect alignment and the design of the parts permitting of quick and easy construction and assembly; and the invention consists in the novel features and combinations hereinafter set forth and claimed.

In the drawings, Fig. 1 is a side elevation of the wrench with the jaws opened to their widest adjustment. Fig. 2 is an edgewise elevation of the wrench head from the adjusting and fixed jaw side; and Fig. 3 is a similar elevation of the opposite side of the wrench showing the rotatable holding nut for the adjusting screw and the strong dovetail construction of the holding portion of the adjustable jaw. Fig. 4 is a perspective view of the adjustable jaw removed from the wrench head showing the novel construction of the same. Fig. 5 is a sectional view of the entire wrench head showing the construction of the adjusting mechanism for the movable jaw. Fig. 6 is a side elevation of the adjusting screw; and Fig. 7 is a perspective view of the round rotatably mounted nut for the end of said screw to hold it firmly in position while adjusting the movable jaw. Fig. 8 is an edgewise elevation of the wrench head without the movable jaw and adjusting screw, showing the dovetail-shaped slot therethrough.

Like characters of reference refer to corresponding parts in the several views.

The wrench belongs to the class of adjustable jaw wrenches in which one of the jaws is a fixed jaw integral with the head and handle of the wrench, and the other jaw is adjustably placed opposite said fixed jaw, the head having a slot with dovetail-shaped holding side walls within which a dovetail-shaped extension of a movable jaw is slidably retained.

The wrench consists of a handle 10 which is preferably placed at an angle to the faces of the jaws instead of in line therewith so that a longer sweep is given to said wrench handle in turning the bolt nut.

The numeral 11 designates the wrench head which has the fixed jaw 12 thereon, the inner face of said jaw adjacent the head having angular braces to strengthen said

fixed jaw. The bracing portions extend from the fixed jaw 12 onto the wrench head 11 each side of a central crosswise slot 14.

The wrench head 11 has, as stated, a slot 14 extending therethrough, which slot has dovetail-shaped side conformations 15 in its walls 16, and a round unthreaded lower portion 17 to rotatably receive therein the threaded adjusting screw 18. Said slot 14 extends through the wrench head 11 including the fixed jaw 12. The wrench head 11 preferably has a notch 19 beneath said fixed jaw 12 to receive the nurled adjusting head 20 of the adjusting screw 18 for the manual actuation of the same. The opposite end of the round opening portion 17 of the slot 14 has a round enlargement or countersunk portion 21 within which the round nut 22 rotatably fits so that when turned onto the end 75 of the adjusting screw 18, it holds said adjusting screw firmly in position in adjusting the movable jaw 23, yet does not extend beyond the wrench head.

The movable jaw 23 has the dovetail-shaped extension 24 which slidably fits within the dovetail-shaped slot 14, so that when in position within said slot and braced by the adjusting screw 18, the movable jaw 23 is firmly and bracingly held in position 85 throughout its entire adjustment. The portion 25 of the jaw 23 extends downwardly toward the adjusting screw 18 and is correspondingly threaded to mesh in said adjusting screw, preferably with a buttressed 90 thread facing toward the fixed jaw 12 and head 20 so that said adjustable jaw 23 is firmly held in alignment by the straight sides of said buttressed thread, and forms as it were rack-teeth 26 in said lower edge of said movable jaw extension. Said buttressed thread 26 is preferably cut in said extension 25 by clamping four of the movable jaws 23 at substantially right angles to one another so that they may be drilled and the buttressed thread 26 may be cut simultaneously in four jaws, as will be readily understood.

The dovetail-shaped construction for the movable jaw 23 holds said jaw firmly in alignment as hereinbefore stated. It also permits a lighter head construction for the wrench which assists in taking the strain in starting nuts, since it bracingly holds the wrench jaws to their work.

What is claimed as new is:

1. In a wrench, a wrench head having a fixed jaw and having a slot crosswise there-

110

105

through with a dovetail-shaped opening therein superimposed upon a smooth round opening, an adjustable jaw having a dovetail-shaped extension slidably and conformably fitting in said dovetail-shaped opening and having rack teeth in its lower edge extending into said smooth round opening, a screw rotatably fitting in said smooth round opening in said head and meshing with said 10 rack teeth in said movable jaw to adjust the same, and means to rotate said screw.

2. In a wrench, a wrench head having a fixed jaw and having a crosswise slot therethrough with a dovetail-shaped opening therein superimposed upon a round smooth lower portion of said opening, an adjustable jaw having a dovetail-shaped extension slidably and conformably fitting in said dovetail-shaped portion of said opening, said adjustable jaw having rack teeth on said extension which extend into said round smooth portion of said opening, a suitably threaded screw fitting in said round smooth portion of said opening having a nurled head on one 20 end for adjusting the same and a round nut on the opposite end for holding said screw in said round smooth opening, said round smooth opening having an enlargement at one end to rotatably receive said round nut 30 on said adjusting screw.

3. In a wrench, a head having a fixed jaw and having a slot crosswise therethrough with a dovetail-shaped opening therein superimposed upon a round smooth lower 35 portion of said opening, an adjustable jaw

having a dovetail-shaped extension slidably and conformably fitting in said dovetail-shaped portion of said opening and having buttress-shaped teeth on its lower edge which extend into said round smooth portion of 40 said opening, a screw having a buttress-shaped thread fitting in said round smooth portion of said opening, said screw having a nurled head on one end for adjusting the same and a round nut for holding the opposite end of said screw, said head having a notch therein on the under side of said fixed jaw to receive said nurled head of said adjusting screw, said round smooth portion of said opening having a round smooth enlargement to rotatably receive said round nut on 45 said adjusting screw, said buttress-shaped teeth on said extension fitting in said buttress-shaped thread on said adjusting screw 50 to adjust said movable jaw as desired. 55

4. In a wrench having a fixed jaw at one side of the wrench head, a slot in said head extending under said jaw and open at the top, said slot being determined by side walls having at the upper edges downwardly opening dovetail conformations, and an adjustable jaw having an extension which slidably fits in said slot within said dovetail conformations thereby functioning to assist said side walls in resisting any tendency to separate under strain.

In testimony whereof I have affixed my signature.

NELS A. JOHNSON.
